UNITED STATES PATENT OFFICE.

PER FRENELL, OF GOTTFENBORG, SWEDEN.

PENCIL SHARPENER.

Application filed February 27, 1923. Serial No. 621,570.

To all whom it may concern:

Be it known that I, PER FRENELL, civil engineer, subject of the King of Sweden, residing at Kopmansgatan 52, Gottenborg, 5 in the Kingdom of Sweden, have invented certain new and useful Improvements in Pencil Sharpeners; and I do hereby declare the following to be a full, clear, and exact description of the invention, such as 10 will enable others skilled in the art to which it appertains to make and use the same.

The present invention has for its object improvements in apparatus for the sharpening of lead pencils or the like (so-called 15 pencil sharpeners) of the type where the cutter or cutters are connected in such a manner with a shaft rotatably arranged in a supporting frame, that during the revolution of the shaft the part of the pencil 20 which is to be sharpened, while it is being fed through a holder for the pencil in the path of the rotating edges, will be cut or sharpened along corresponding cuts or sections arched in relation to the longitudinal 25 axis of the pencil.

According to the present invention the cutters consist of knife blades, for example of double edged safety razor blades, or the like blades, which are detachably fitted in 30 arms or the like projecting from the rotating shaft the outer surface of which arms are so bent or shaped that the blades resting against said surface in working position are arched in cross-section, whereas 35 the cutting edges of said blades are so formed or arranged that they extend substantially lengthwise of the shaft whereby the advantage of an efficient construction is gained.

40 In order to facilitate the cutting during the sharpening process and at the same time to utilize the cutter blades in the best way the cutter is according to one form of the invention arranged in such a way 45 that during the revolution of the shaft, the shaft itself or the parts carrying the cutter blades are given a slow reciprocating movement lengthwise of the shaft.

It is before known to use razor blades 50 of the kind mentioned for sharpening of lead pencils, for instance in such a way that the edges of the blade have their principal extension lengthwise of the pencil, which, however, is connected with some 55 drawbacks obviated by the present invention, but as far as I know it is not before

known in apparatuses above described to have the blades arranged in the manner described in the present patent.

In order, however, to facilitate the cutting 60 during the sharpening process, in one form of the present invention the cutters are arranged in such wise that during the revolution of the shaft they are subjected not merely to the rotary motion, but at 65 the same time also to a slow reciprocating motion in relation to the pencil or the supporting frame, in addition to which arrangements are provided for the automatic feeding and rotation of the pencil accord- 70 ing as the sharpening proceeds. Blades of safety razors of the so-called Gillette type can, in accordance with the present invention, be used with advantage as cutters.

The advantages of the use of razor blades 75 of the type above referred to are that they are excellently adapted for the purpose, and moreover that they can easily be procured as they are sold everywhere. Razor blades of the above mentioned type which have 80 been used for their original purpose, i. e. those which have been discarded for the purpose of shaving can very well be used for the sharpening of pencils, in which case the cost of the knives or cutters will be 85 very small or negligible. These razor blades are suitable also for the reason that they can very easily be curved or bent in the manner required for the purpose in question. Obviously, blades specially manu- 90 factured for the purpose can also be employed.

In order to make plain the invention, an example thereof is shown in the accompanying drawing. Fig. 1 shows the pencil 95 sharpener viewed from above. Fig. 2 shows a vertical section along the line 2—2 in Fig. 1. Fig. 3 shows a vertical section along the line 3—3 in Fig. 1. Fig. 4 shows in vertical section a detail of a guiding and feeding device for the pencil in a certain working position during the sharpening. Fig. 5 shows a detail, Figs. 6 and 7 show another detail in two different working 100 positions. Figs. 8, 9, 10 and 11 show viewed 105 from above and from the side respectively details of the clamping device illustrated in Figs. 6 and 7.

The pencil sharpener consists of a supporting frame 13, provided with a covering 110 or casing 17, and with a shaft 16 rotatably journaled in the latter, on which shaft are

arranged holders, arms or the like 1, which carry cutters 30, which, if, as shown in the drawing, they consist of such thin blades as are used in safety razors of the Gillette type, may be fixed to the holders 1 by means of a screw 54 provided with a suitable head 2 and a wing nut 3. As is shown in Fig. 3, the head 2 and the corresponding part of the holder 1 are so shaped that the blade 30 will be arched in cross section, and the outer surface of the head 2 is so rounded and shaped that it does not project beyond the cylindrical surface which, on the revolution of the shaft, is determined or passed by the cutting edges of the knives i. e. the leading edges of the blades when the shaft is rotated in the direction indicated by the arrow in Fig. 3.

During the sharpening process the pencil 20 is inserted in the socket 14 united with the supporting frame 13, and arranged in a known manner, the socket being adjustably fixed to the frame by screws or other suitable means. The socket 14 is provided with 25 another socket 9 rotatably arranged in the latter and adjustable in its longitudinal direction, in which socket 9 the pencil is intended to be inserted and jammed. For this purpose the socket 9 at its upper part is provided with a clamping device for the secure holding of the pencil, comprising a plate 10 fixed to the socket. On the said plate are arranged jaws 11, 12 rotatable round a pivot 33 and provided with teeth 56, 57 (see Figs. 33 and 6-11), which jaws are furnished with clamping plates 58, 59, so that by pressing these plates against one another with the fingers the jaws 56, 57 are moved apart from one another (are opened) in the manner indicated in Fig. 7, so that the pencil can be inserted in the sockets 9 and 14, whereupon, after the clamping plates have been released, the jaws by the action of coil springs 34 attached at their one ends by screws 32 to 40 the plate 10 and at their other ends to each of the clamping plates 58, 59, are brought towards one another so as to grip the pencil.

The socket 9 is further provided with a toothed wheel 7 surrounding it and resting 50 against the socket 14, and said socket is moreover so arranged in the latter socket that it can be displaced in its longitudinal direction in the central opening of the toothed wheel, but on the rotation of the wheel 7 is brought to rotate with the latter. For the latter purpose the socket 9 is provided with two grooves (see Figs. 4, 5) arranged in its lengthwise direction, and the toothed wheel 7 is furnished with two teeth 52, or the like, entering into the said 55 grooves. The radius of the toothed wheel 7 is greater than the radius of the top opening of the socket 14, and it is kept in place even when the socket 9 is lifted or raised 60 through the action of a flange 63 projecting

over the toothed wheel 7 and arranged on the upper part of the socket 14 (see Fig. 4). The toothed wheel 7 gears with a worm 8 formed on or mounted on the shaft 15. The shaft 15 is so arranged that it can be rotated simultaneously with the shaft 16 by means of a toothed wheel 4 provided with a handle 26, which wheel is mounted on a journal 19 fixed in the covering; the said wheel 4, which is provided with inward 75 teeth, is in mesh with toothed wheels 5 and 6 arranged respectively on the shafts 15 and 16. Under the socket 9 a rest or shoulder 27 for the tip of the pencil is adjustably fixed to the covering, which rest or shoulder can 80 be adjusted at different heights by a set screw 60, or other suitable means. The covering is moreover provided with a jointed lid 61 mounted on hinges 55 and provided with a locking device 20, and a drawer 18 85 for the reception of the shavings is moreover arranged in the supporting frame. In order to enable the entire length of the cutters to be utilized in the sharpening, and in order to obtain an oblique mode of cutting adapted for the intended purpose, that is, so that the cutting takes place simultaneously both along the pencil, i. e. essentially in the direction in which the fibres run, and along the edges of the cutter or cutters, 95 the latter are arranged in such wise that, as indicated above, they are subjected not merely to the rotary motion but also to a slow reciprocating motion in relation to the pencil which is to be sharpened i. e. in relation to the supporting frame 13. This may be effected either by imparting to the shaft 16 carrying the cutters, by a device suitable for the purpose, a slow longitudinal reciprocating motion in relation to the supporting frame, the knives also participating in that motion or else by arranging the knives or knife-holders in such wise as to impart to them, during the revolution of the shaft, a slow reciprocating axial motion in 100 relation to the shaft. On the appended drawing is shown an example of the last-mentioned device, in which the shaft is rotatable, but in the axial direction not displaceably arranged in the supporting frame. 105

According to the example shown in the drawing, the shaft 16 for the aforesaid purpose is provided with a screw-formed groove 53, extending symmetrically round the shaft and forming a closed path; the 110 groove extending along the shaft for a distance corresponding to the required lengthwise movement of the knives (see Fig. 2). In the nave 62 of the holder 1 for the knives a ball, roller, or the like, 29 is journaled, 115 part of it entering into the aforesaid groove. By this arrangement the holder 1, on the rotation of the shaft 16 for the purpose of the sharpening, will participate in the rotation of the shaft 1 but, owing to the re- 120

sistance of the pencil to the cutters, the revolution of the holder will be retarded somewhat in relation to the revolution of the shaft, as the ball will run into the groove 53, whereby a slow reciprocating motion, corresponding to the shape and extent, in an axial direction, of the groove 53, will be communicated also to the holder. The greater the resistance of the pencil to the cutters, 5 the greater will be the retardation or drag of the holder in relation to the rotary motion of the shaft, and thereby also the reciprocating motion of the holder in the lengthwise direction of the shaft. This motion, 10 however, can also be regulated somewhat by varying the degree of tension with which the ball is jammed into the groove 53, whereby the friction is increased (or diminished). The regulation of this tightening or "jamming" 15 can be effected by means of the screw 25 screwed into the nave 62 of the holders 1, which screw rests at its inner end against the ball. The said screw may suitably be provided with a lock-nut 28, so that it can 20 be locked in the desired position. The ball 29 may be inserted or removed for the purpose of renewal, by removing the screw 25. It should be obvious that, instead of using the ball 29, it is also possible to arrange a 25 pin or the like which enters into the groove 53, for the purpose of the required movable locking of the shaft 16 and the knife-holders to one another. It should also be manifested that, instead of arranging the groove 30 53 on the shaft, it is also possible to arrange a corresponding groove in the inner surface, resting against the shaft, of the nave 62, the yielding locking of the holder to the shaft being effected with the aid of a device analogous to that above described.

Analogous devices may also be employed in order to effect the reciprocating motion of the shaft lengthwise in relation to the supporting frame, or the pencil; for example, 45 the ball 29, or a corresponding pin, may be journalled in a fixed position in relation to the supporting frame and enter into a groove in the shaft, corresponding to the groove 53. For the said purpose also other generally known devices may obviously be employed, 50 such as cam surfaces, or the like, suitably formed, against which the shaft, for example by the action of springs, is pressed, and is consequently compelled during the rotation to move to and fro in a lengthwise direction.

The pencil sharpener is used and operates in the following manner:

When a pencil is to be sharpened, the 60 socket 9 is pulled up some distance out of the socket 14, and the jaws 11, 12 are caused to open (see Fig. 7) by pressure against the clamping plates 58, 59, whereupon the pencil is slipped down or inserted into the socket 65 and is gripped by the jaws, on the release of

the clamping plates (see Fig. 6). On the turning of the toothed wheel 4 by means of the handle 26 the shafts 15 and 16 are set in rotation. The holder 1 arranged on the shaft 16 together with the cutters fixed to it will 70 thereby be brought to rotate, during which rotation the cutters will come into contact with the lower part of the pencil and sharpen it. Owing to the rotation of the shaft 15 the socket 9 and the pencil inserted therein will 75 also be rotated, so that the pencil, according as the sharpening proceeds, will be lowered into the socket 14 until the tip of the pencil finally rests against the adjustable shoulder 27, whereupon the sharpening automatically 80 ceases. During the sharpening as has been indicated above, the cutters will move slowly to and fro in an axial direction in relation to the pencil, so that almost the entire length of the cutting edges will participate in the 85 sharpening, whence the cutters will be utilized in the best possible way. According to the example shown in the drawing, the cutters have straight edges arranged parallel with the shaft 16. It should, however, be 90 obvious that the cutting edges may run obliquely or screw-wise in relation to the shaft 16, provided only that they are so arranged that all cutting parts of the edges lie at the same radial distance from the geometric axis 95 of the shaft 16, i. e. lie in the same cylindrical surface. By this arrangement of the edges an advantageous mode of cutting is also secured. It should be evident from the above that by the described devices the 100 sharpened part of the pencil will not be given the shape of a cone with a rectilinear generator, but the shape of a cone whose generator forms part of an arc of a circle which during the rotation is described by 105 the edges of the cutters, and that thus the exposed part of the lead approaches more closely to a cylindrical shape than the formed part of the wood, so that the lead will be given a shape particularly suitable 110 for use, and very durable.

Having thus described my invention I declare that what I claim is:

1. A pencil sharpener comprising a supporting frame, a pencil holder associated therewith, a rotary shaft mounted in the frame, knife supporting arms projecting radially from said shaft, flexible knife blades carried by said arms so that the cutting edges are transversely disposed with respect to the axis of the pencil and rotate in a cylindrical plane about the axis of said shaft, said arms having curved knife seats and means for detachably clamping the knife blades against said seats whereby the blades are arched in cross-section.

2. A pencil sharpener comprising a supporting frame, a pencil holder associated therewith, a rotary shaft mounted in the frame, knife supporting arms projecting

4. radially from said shaft, flexible knife blades carried by said arms so that the cutting edges are transversely disposed with respect to the axis of the pencil and 5 rotate in a cylindrical plane about the axis of said shaft, said arms having curved knife seats, means for detachably clamping the knife blades against said seats whereby the blades are arched in cross-section and means for reciprocating the knives in a direction axially of the shaft. 10
5. A pencil sharpener comprising a supporting frame, a pencil holder associated therewith, a rotary shaft mounted in the frame, knife supporting arms projecting radially from said shaft, flexible knife blades carried by said arms so that the cutting edges are transversely disposed with respect to the axis of the pencil and 15 rotate in a cylindrical plane about the axis of said shaft, said arms having curved knife seats, means for detachably clamping the knife blades against said seats whereby the blades are arched in cross-section and means whereby rotation of said 20 shaft causes reciprocation of said arms axially of the shaft.
6. A pencil sharpener comprising a supporting frame, a pencil holder associated therewith, a rotary shaft mounted in the frame, knife supporting arms projecting radially from said shaft, flexible knife blades carried by said arms so that the cutting edges are transversely disposed with respect to the axis of the pencil and 25 rotate in a cylindrical plane about the axis of said shaft, said arms having curved knife seats, means for detachably clamping the knife blades against said seats whereby the blades are arched in cross-section and means whereby rotation of said 30 shaft causes reciprocation of said arms axially of the shaft.
7. A pencil sharpener comprising a supporting frame, a pencil holder associated therewith, a rotary shaft mounted in the frame, knife supporting arms projecting radially from said shaft, flexible knife blades carried by said arms so that the cutting edges are transversely disposed with respect to the axis of the pencil and 35 rotate in a cylindrical plane about the axis of said shaft, said arms having curved knife seats, means for detachably clamping the knife blades against said seats whereby the blades are arched in cross-section and means whereby rotation of said shaft causes reciprocation of said arms axially of the shaft, said means comprising a groove in the shaft and ball associated with said arms, and a screw removably holding said ball in place and capable of adjusting the pressure on the ball. 40
8. A pencil sharpener comprising a supporting frame, a pencil holder associated therewith, a rotary shaft mounted in the frame, knife supporting arms projecting radially from said shaft, flexible knife blades carried by said arms so that the cutting edges are transversely disposed with respect to the axis of the pencil and 45 rotate in a cylindrical plane about the axis of said shaft, said arms having curved knife seats, means for detachably clamping the knife blades against said seats whereby the blades are arched in cross-section and means whereby rotation of said shaft causes reciprocation of said arms axially of the shaft, said means comprising a groove in the shaft and ball associated with said arms, and a screw removably holding said ball in place and capable of adjusting the pressure on the ball. 50
9. A pencil sharpener comprising a supporting frame, a pencil holder associated therewith, a rotary shaft mounted in the frame, knife supporting arms projecting radially from said shaft, flexible knife blades carried by said arms so that the cutting edges are transversely disposed with respect to the axis of the pencil and 55 rotate in a cylindrical plane about the axis of said shaft, said arms having curved knife seats, means for detachably clamping the knife blades against said seats whereby the blades are arched in cross-section and means whereby rotation of said shaft causes reciprocation of said arms axially of the shaft, said means comprising a groove in the shaft and ball associated with said arms, and a screw removably holding said ball in place and capable of adjusting the pressure on the ball. 60
10. A pencil sharpener comprising a supporting frame, a pencil holder associated therewith, a rotary shaft mounted in the frame, knife supporting arms projecting radially from said shaft, flexible knife blades carried by said arms so that the cutting edges are transversely disposed with respect to the axis of the pencil and 65 rotate in a cylindrical plane about the axis of said shaft, said arms having curved knife seats, means for detachably clamping the knife blades against said seats whereby the blades are arched in cross-section and means whereby rotation of said shaft causes reciprocation of said arms axially of the shaft, said means comprising a groove in the shaft and ball associated with said arms, and a screw removably holding said ball in place and capable of adjusting the pressure on the ball. 65
